UNITED STATES PATENT OFFICE

JAMES M. COUGHLIN, OF WILKES-BARRE, AND OSCAR P. ROSS, OF KINGSTON, PENNSYLVANIA, ASSIGNEES TO WILKES-BARRE CAN COMPANY, OF WILKES-BARRE, PENNSYLVANIA, A CORPORATION OF PENNSYLVANIA

VASE

Application filed November 2, 1928. Serial No. 316,777.

This invention relates to a vase designed primarily for use in cemeteries, gardens, and the like, one of the objects being to provide a vase the body or container portion of which has a supporting stem detachably connected thereto in a new and novel manner whereby to facilitate shipment of the vase and also to permit vases and their supporting stems to be interchanged readily.

10 A further object is to provide a device of this type which is inexpensive and the supporting means of which will serve to hold the base firmly in any position desired upon or close to the ground where it will not fall over or be readily displaced.

With the foregoing and other objects in view which will appear as the description proceeds the invention resides in the combination and arrangement of parts and 20 in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is an elevation of the device, 30 a portion thereof being broken away to show, in section, the interfitting portions of the body and holder.

Figure 2 is a bottom plan view of the body and holder of the vase.

35 Figure 3 is a perspective view of the holder.

Referring to the figures by characters of reference, 1 designates a vase of any suitable size and configuration. It is prefer-

40 ably formed of sheet metal and may be suitably ornamented. This vase, in the form shown, is tapered downwardly toward its base and has a bottom in the form of a disk 2 provided with an annular flange 3. This

45 flange is fitted snugly in the end of the body and is clinched or otherwise held thereto.

In the recess defined by the flange 3 is formed an annular rib 5 pressed inwardly from the flange and this rib cooperates with 50 the bottom 2 to form an annular groove 6.

The holder is formed preferably of a length of stiff wire bent to provide an elongated stem 7 one end of which is extended radially as at 8 and merges into a split ring 9 concentric with the longitudinal axis of 55 the stem. The material of which the stem and its ring are formed is preferably resilient. The diameter of the split ring or spring loop 9 is slightly greater than the inner diameter of the rib 5. Thus by inserting 60 the split ring into the lower end portion of the space defined by the flange 3 and then forcing the ring toward the bottom 2, said ring will be contracted by contact with the rib 5. After the ring passes the rib it will 65 expand into the groove 6, thereby frictionally engaging the flange 3 above the rib 5 and holding the body 1 secured to the stem 7.

The stem can be forced downwardly into the ground so as to support the body 1 on 70 the surface of the ground or at any desired distance thereabove. Obviously the stem 7 can be made of any length desired.

When shipping the vase the stem can be removed by exerting a sufficient pull thereon 75 to cause the ring 9 to contract and withdraw from the groove 6. Said stem can then be placed in the body of the vase and the entire article wrapped and shipped.

If a long stem is employed and it is not 80 desired to remove the same from the ground every time the vase is to be handled, said stem can be left in the ground and the vase can be forced off of the ring 9 whenever it is desired to handle it for any purpose. 85 Thereafter the vase can be returned to proper position, placed over the ring 9 and forced downwardly until the ring snaps into the groove 6.

From the foregoing, it will be apparent 90 that the present invention provides a metal receptacle adapted to serve as a flower holder or vase, having a flat bottom portion adapted to constitute keeper means for a releasable prong device. The said prong device is formed by a single piece of spring wire which is bent at one end as indicated at 8 and 9 to provide an annular metallic spring member adapted to releasably engage behind the ring 5, and also bent at 95 100

right angles to the portion 8-9 to provide a relatively long prong 7 for entering the ground or other surface.

What is claimed is:

- 5 1. In a flower holder or vase, a metal receptacle, a releasable prong device comprising an annular metallic spring member terminating at one end in a portion bent radially to and extending inwardly from the annular portion to a point adjacent the centre of the annular member and lying substantially in the plane thereof, said radial portion terminating in a relatively long prong bent to extend at right angles to the radial portion and annulus, and a flange integral with said receptacle and projecting below the bottom thereof for releasably receiving and supporting said annular spring member under tension whereby said prong will extend downwardly from substantially the centre of the receptacle.
- 10 2. In a flower holder or vase, a metal receptacle, a releasable prong device comprising an annular metallic spring member terminating at one end in a portion bent radially to and extending inwardly from the annular portion to a point adjacent the centre of the annular member and lying substantially in the plane thereof, said radial portion terminating in a relatively long prong bent to extend at right angles to the radial portion and annulus, said annular, radial and prong portions being formed from a single piece of wire of the same gauge, and a flange integral with said receptacle and projecting below the bottom thereof for releasably receiving and supporting said annular spring member under tension whereby said prong will extend downwardly from substantially the centre of the receptacle.
- 15 3. In a flower holder or vase, a metal receptacle, a detachable prong device comprising a single piece of spring wire bent to provide an annular spring loop and having a prong device bent at right angles to the loop and connected therewith and extending longitudinally from the axis of the loop, and means on the lower end of the receptacle for providing a keeper recess to receive the annular spring loop portion of the releasable prong device.
- 20 4. In testimony that we claim the foregoing as our own, we have hereto affixed our signatures.

JAMES M. COUGHLIN.
OSCAR P. ROSS.
